(57) **CLAIM**

The ornamental design for a display screen or portion thereof having a graphical user interface, as shown and described.

DESCRIPTION

FIG. 1 is a front view of the display screen or portion thereof having a graphical user interface in accordance with a first embodiment showing my new design; and,

FIG. 2 is a second embodiment thereof.

The broken lines in the drawings illustrate the display screen or portion thereof which form no part of the claimed design. The remaining broken lines showing portions of the graphical user interface form no part of the claimed design.

1 Claim, 2 Drawing Sheets
